UNITED STATES PATENT OFFICE

EDWARD S. SMITH, OF WATERBURY, CONNECTICUT.

SHOE-CLASP.

SPECIFICATION forming part of Letters Patent No. 372,576, dated November 1, 1887.

Application filed September 22, 1887. Serial No. 250,398. (No model.)

To all whom it may concern:

Be it known that I, EDWARD S. SMITH, of Waterbury, in the county of New Haven and State of Connecticut, have invented a new Improvement in Shoe-Clasps; and I do hereby declare the following, when taken in connection with accompanying drawings and the letters of reference marked thereon, to be a full, clear, and exact description of the same, and which said drawings constitute part of this specification, and represent, in—

Figure 1, a top view of the clasp with the lever in the open position; Fig. 2, a side view showing the lever in the closed position; Fig. 15 3, a longitudinal central section with the lever in the closed position; Fig. 4, a central section with the lever in the open position, the spring broken away to show the stop; Fig. 5, a transverse section through the notches with the lever in the open position, and illustrating the stops as bearing upon the pivot end of the lever; Fig. 6, the plate A detached; Fig. 7, the spring-plate B detached; Fig. 8, the blank from which the tongue is formed; Fig. 9, an edge 20 view of the tongue detached.

This invention relates to an improvement in that class of buckles or clasps designed for overshoes, in which the clasping device consists of a plate fixed to a standing strap, a 30 hook-shaped lever hinged to said plate by the hook-shaped end of the lever, and so that the lever may turn down onto the plate in its closed position, leaving a space between the body of the lever and the plate at the hinge or hook 35 end, combined with a loop, also fixed to a standing strap, and so that the lever turned away from its plate into its open position may be introduced through the said loop, and then by returning the lever and the frame to its closed 40 position the loop will be drawn into the hook-shaped part of the lever and close upon the pivot, and a spring upon the said plate adapted to bear upon the hinge end of the lever, so as to retain it in its closed or engaged position or 45 permit it to be opened—a class of clasps well known in the trade.

In the more general construction of this class of clasps the frame is made in two parts or plates, substantially alike—one or both elastic—the two plates secured together at one end

and bifurcated at the other end, so that the lever may be hung between them. The pivots on the hook are flat, and the seats for the pivot are formed by making recesses in the two legs of one or both plates and between the plates, 55 so that the pivots and the pivot end of the lever act like cams against the spring to separate the spring and plate as the lever is turned from one extreme to the other, the spring yielding under the said cam-like action, and then by its reaction forcing the lever into either of its extreme positions. The recess in the frame for the hinge has usually been made by 60 depressions in the surface of one or both of the plates.

The object of my invention is a cheap and simple construction and one in which certain difficulties existing in the usual construction of this class of clasps, and which will herein-after appear, are avoided.

In carrying out my invention I construct the frame of two plates, A B. (Shown detached in Figs. 6 and 7.) The plate A is preferably made of U shape; but in any case one end is bifurcated to form legs C D. Both plates are 75 preferably cut from sheet-steel, or other suitable elastic metal, and of a thickness according to the strength of the buckle required. Upon the inner side of both legs the edge is turned upward, and in the turned-up edge at 80 each side a notch, a, is formed. The outer portions of the turned-up edge form ears b b. The inner portions of the turned-up edge also form ears d d. The ears b stand in a plane at right angles to the plane of the arms C D; but the 85 upper ends of the ears d d are both turned toward each other and over the space between the legs, as clearly seen in Fig. 6, and so that the space between the two ends of the ears d d is narrower than the space between the two legs 90 proper.

The second plate, B, is preferably made in shape corresponding to the plate A, but instead of terminating in two legs at one side it terminates in a tongue, E, narrower than the 95 space between the two legs C D of the plate A, and so as to set upon the frame and bring the tongue between the two ears d d, as seen in Fig. 1. The shape of the body of the two plates is, as before stated, preferably alike, 100

and so that when set together, as seen in Fig. 1, there will be an opening, F, through both plates, by which the clasp may be connected to the strap.

5 The two plates are best secured together by forming projecting flaps G G on one part, A, as seen in Fig. 6, and then, when the two plates are set together, closing the two flaps G G over the plate B, as seen in Figs. 1 and 2; but the 10 two plates may be otherwise secured—say as by rivets, indicated in broken lines, Fig. 1.

H represents the lever. This is cut from sheet metal, as seen in Fig. 8. At one end it is of a width corresponding substantially to 15 the width between the two legs C D of the plate A, and at that end lateral projections e are formed, in width corresponding substantially to the width of the notches a between the ears b d. These projections e are flat, as 20 seen in Fig. 9, and form the pivots upon which the lever is to turn. At the opposite end the lever terminates in any convenient shape, to serve as a handle for operating the lever. The lever is bent into hook shape at the pivot end, 25 and so that the pivots will stand distant from the body of the hook, but in a plane substantially parallel therewith. The pivots are introduced between the tongue E of the plate B and into the notches a a of the plate A, and, 30 as represented in Fig. 1, the elasticity of one or both plates permitting such introduction of the lever after the plates are secured together, if preferred. This brings the tongue E to bear upon one side of the pivot end, while the 35 other side rests in the notches a a in the plate A. The lever being in the closed position, as seen in Fig. 3, the tongue E rests upon the pivot end of the lever inside the hook, and serves to hold the handle end of the lever 40 down upon the other end of the plate and in its closed position. If, now, the free end of the lever be raised, it will turn upon the pivots, and owing to the flat shape of the pivots they act as cams between the legs C D and the 45 tongue E, and the tongue being naturally the more elastic will yield under the cam-like action of the lever, as indicated in broken lines, Fig. 2, until the lever is so far turned as to incline the reverse side of the pivot end of 50 the lever to the spring. Then the reaction of the spring will serve to throw the lever to its extreme open position, as seen in Fig. 4, and as also seen in Fig. 1. In this open condition the loop is applied to the lever in the usual 55 manner. Then the lever returned, will raise the spring, as before, until the lever is so far returned as to permit the spring to work over the pivot end of the lever, when the spring will again react and serve to throw the lever 60 into the closed position, as seen in Figs. 3 and 2. This action of the spring upon the lever, in combination with the flat pivots, is common and well known, and is the same in this clasp as in others.

65 In producing the notches a to receive the pivot, by turning the inner edge of the legs

upward to form the ears b d, I avoid the depressions in the legs or plates, and the under surface of the plate is therefore left flat and smooth.

70

As the lever is thrown to the open position, as seen in Fig. 4, were there nothing to stop it, it would be free to be turned beyond that open position. In so doing it will act as a cam against the spring, and owing to the hook 75 shape or projection of the lever beyond the pivots the cam action would be so great that the spring would be liable to be broken. To produce a stop which shall prevent such possible accidental working of the spring or 80 tongue E, the ears d, one or both, are turned inward, as represented in Fig. 6, and so as to extend over the pivot end of the lever when it is in its open position, and as seen in Fig. 4; hence when the lever is thrown to the wide- 85 open position, or substantially there, the lever back of the pivots will come to a bearing against the stops d, and further turning of the lever is prevented. Consequently the cam-like 90 action of the lever upon the spring, which would occur by turning it beyond the wide-open position, is avoided.

85

It will be evident that turning inward one of the ears d only will be sufficient to form a stop for the lever in its wide-open position— 95 that is, the turned-in portion of one may be omitted, as indicated in broken lines, Fig. 6. Therefore, while preferring to turn the ears d d inward alike, I do not wish to be understood as limiting this part of the invention to the turning in of both ears.

100

I claim—

1. The herein described clasp, consisting of two sheet-metal plates, A B, secured together at one end, the opposite end of the plate A 105 bifurcated, the inner edge of the legs turned upward from the plate at substantially right angles thereto, the said turned-up edges having a notch, a, formed in each as a seat for the pivot, the other plate, B, having its free end 110 narrower than the distance between the two legs of the plate A, forming a tongue, E, which is adapted to rest between the said legs, combined with the hook-shaped lever H, its hook-shaped end constructed with laterally-projecting flat pivots e, corresponding to 115 the notches a in the turned-up edges of the plate A, the said pivots resting upon the plate A in said notches, the free end E of the plate B arranged to bear upon the reverse side of 120 the pivot end of the lever, substantially as described.

115

2. The combination of the plates A and B, secured together at one end, the plate A bifurcated at the opposite end, the inner edge 125 of the two legs turned upward at substantially right angles to the plate, said turned-up edges having a notch, a, formed therein, and so as to produce ears b at the outer end of the legs and ears d upon the opposite side of the 130 notches, the said ears d turned inward toward each other, the free end of the plate B nar-

lower than the space between the legs of the plate A and extending between them, with the hook-shaped lever H, the hook-shaped end constructed with laterally-projecting flat 5 pivots e, the said pivots resting upon the plate A within said notches, while the free end of the plate B, between the said legs, bears upon the reverse side of the pivot end of the lever, the said turned-in ears d forming a stop for the lever in its open position, substantially as 10 described.

EDWARD S. SMITH.
